UNITED STATES PATENT OFFICE.

CARL BETTERMANN, OF HAGEN, GERMANY, ASSIGNOR TO KRUPP PATENT-PLATTEN-GUSSFORM-VERTRIEB G. M. B. H., OF HAGEN, IN WESTPHALIA, GERMANY.

MOLD FOR PRODUCING MOLDED STONE SLABS.

Application filed October 20, 1925. Serial No. 63,746.

To all whom it may concern:

Be it known that I, CARL BETTERMANN, residing at Hagen, i. Westphalia, Germany, a citizen of the Republic of Germany, have invented certain new and useful Improvements in Molds for Producing Molded Stone Slabs, of which the following is a specification.

This invention relates to box-like molds for the production of molded stone slabs with a flat Z-shaped cross section, and the object of the invention is to enable a large number of such slabs to be produced simultaneously in a simple manner.

According to the invention, the mold has two side walls situated opposite to one another and carrying projections arranged in the form of a comb and reaching from the base of the mold to its upper edge, said projections of the one side wall being staggered to those of the other side wall, the gaps between two adjacent projections on one side wall being subdivided by transverse partitions which reach to the projections of the other side wall opposite said gaps.

In the drawing:

Figure 1 is an end elevation of a mold for cast slabs forming an embodiment of the invention by way of example.

Figure 2 is a side elevation thereof.

Figure 3 is a top plan partially in section of the mold.

Figure 4 is a cross section of a wall which is composed of the slabs produced in the casting mold shown in Figures 1 to 3.

A denotes the base plate of the box-like casting mold to which the side walls B and the end walls C of the mold are pivotally attached by bolts a^1 and a^2 , so that the mold can be opened by turning down the side walls B and C. On each of the two side walls B are arranged after the manner of a comb, Figure 3, a number of projections b^1 of trapezoid cross section extending from the base up to the upper edge of the mold. These projections are so arranged that each gap between adjacent projections b^1 of one side wall is opposite a projection on the other side wall. Each such gap is subdivided by a transverse partition D loosely inserted into the mold, Figure 3, and extending up to the projection b^1 on the other side wall opposite the gap, so that a hollow space of the cross sectional form of the flat Z-shaped slabs E, Figure 4, to be produced is

formed between every two adjacent transverse partitions D and the parts of the projections b^1 opposite to them. Between each end wall C and the adjacent partition D the hollow space on the side of the gap which contains the transverse partition (D) is of the same width throughout, so that here a hollow space of the cross sectional form of an end slab E¹, adapted to limit a wall or floor to be composed by the slabs is formed, see Figure 4. The loosely inserted partitions D are held in position by a longitudinal bar F, which is affixed in an easily detachable manner to the end walls C by hinged yokes G mounted thereon. To the outside of each side wall B is attached a stiffener bar b^2 , the ends b^3 of which are bent over at right angles and embrace the end walls C claw fashion, see particularly Figure 3. Each of two end walls C carries a screw adjustment device with a screw nut H provided with a right and left-handed screw thread, and is adapted to rotate on two spindles J which are guided longitudinally on the end wall C and provided with corresponding screw threads. The ends i^1 of these spindles J are adapted to bear against the bars b^2 . To prevent the side and end walls B and C from turning down unintentionally two locking levers K, see particularly Figure 2, are provided on the outsides of the walls B. Each of these locking levers is pivotally mounted on one of the end walls C by a pin c^1 and locked to the other end wall by each locking lever K catching by means of a groove k^1 , see Figure 2, over a screw bolt c^2 fixed to the corresponding end wall and secured in position by a wing nut c^3 , see particularly Figure 2.

When casting, all the parts of the mold are in the position shown in the drawing. After casting as soon as the stone slabs have hardened, the longitudinal bar F is lifted off and the locking levers K after having been unlocked are swung upwards about the axis of the pins c^1 . The two side walls B are then first turned down and then the end walls C now released from the claw-like ends b^3 of the bars. Each slab can then be removed separately and without trouble. In the case of some materials it has been found by experience that the slabs when hardened adhere fairly firmly to the walls of the mold surrounding them. In this case after the locking levers K have been swung upwards 110

and before the bar F has been lifted off, the sides B are forced uniformly apart through the medium of the spindles J by turning the screw nuts H with the right and left-handed screw threads, whereby the projections b¹ become gradually loosened from the cast slabs. The slabs and the partitions are meanwhile held in position by the bars F fixed to the side walls C. After the side walls B have been turned down, the bars F are removed and then the end walls C are also dropped down, thus exposing the cast slabs.

Besides the fact that the above described casting mold enables a large number of slabs to be produced simultaneously in a simple manner, it has also the advantage, because it can be taken to pieces, that each part of the walls of the mold can be easily cleaned from any impurities that may adhere to it, so that castings with a smooth external surface can be satisfactorily produced.

Claims.

1. A mold for casting slabs of flat Z-shaped cross section, comprising a bottom plate, two end walls and two side walls fixed to said bottom plate, said side walls carrying inside each a series of projections arranged in a comb-like manner, the projections of one side wall being staggered relatively to those of the other side wall, a partition arranged in each gap existing between two adjacent projections, said partitions extending from the base of the gaps up to the crests of the projections of the other side wall.

2. A mold for casting slabs of flat Z-shaped cross section, comprising a bottom plate, two end walls and two side walls hinged to said bottom plate so as to be able to be swung down into the plane of the latter, said side walls carrying inside each a series of projections arranged in a comb-like manner, the projections of one side wall being staggered relatively to those of the other side wall, a partition arranged in each gap existing between two adjacent projections, said partitions extending from the base of the gaps up to the crests of the projections of the other side wall.

3. A mold for casting slabs of flat Z-shaped cross section, comprising a bottom plate, two end walls and two side walls hinged to said bottom plate so as to be able to be swung down into the plane of the latter, said side walls carrying inside each a series of projections arranged in a comb-like manner, the projections of one side wall being staggered relatively to those of the other side wall, a partition arranged in each gap existing between two adjacent projections, said partitions extending from the base of the gaps up to the crests of the projections of the other side wall, and easily detachable means for securing said side walls in operative position.

4. A mold for casting slabs of flat Z-shaped cross section, comprising a bottom plate, two end walls, and two side walls hinged to said bottom plate so as to be able to be swung down into the plane of the latter, said side walls carrying inside each a series of projections arranged in a comb-like manner, the projections of one side wall being staggered relatively to those of the other side wall, a partition arranged in each gap existing between two adjacent projections, said partitions extending from the base of the gaps up to the crests of the projections of the other side wall, bars pivoted to one of the end walls and adapted to be put on the side walls taking their operative position, and means for locking said bars in their operative position.

5. A mold for casting slabs of flat Z-shaped cross section, comprising a bottom plate, two end walls and two side walls hinged to said bottom plate so as to be able to be swung down into the plane of the latter, said side walls carrying inside each a series of projections arranged in a comb-like manner, the projections of one side wall being staggered relatively to those of the other side wall, a partition arranged in each gap existing between two adjacent projections, said partitions extending from the base of the gaps up to the crests of the projections of the other side wall, easily detachable means for securing said side walls and said partitions in operative position.

6. A mold for casting slabs of flat Z-shaped cross section, comprising a bottom plate, two end walls and two side walls hinged to said bottom plate so as to be able to be swung down into the plane of the latter, said side walls carrying inside each a series of projections arranged in a comb-like manner, the projections of one side wall being staggered relatively to those of the other side wall, a partition arranged in each gap existing between two adjacent projections, said partitions extending from the base of the gaps up to the crests of the projections of the other side wall, bars pivoted to one of the end walls and adapted to be put on the side walls taking their operative position, locking means for said bars in their operative position, a bar extending from one end wall to the other in order to lock said partitions in position, and locks on said end walls for holding said last-named bar in locking position.

7. A mold for casting slabs of flat Z-shaped cross section, comprising a bottom plate, two end walls and two side walls hinged to said bottom plate so as to be able to be swung down into the plane of the latter, said side walls carrying inside each a series of projections arranged in a comb-like manner, the projections of one side wall being staggered relatively to those of the other

- side wall, a partition arranged in each gap existing between two adjacent projections, said partitions extending from the base of the gaps up to the crests of the projections 5 of the other side wall, bars pivoted to one of the end walls and adapted to be put on the side walls taking their operative position, locking means for said bars in their operative position, a bar extending from one 10 end wall to the other in order to lock said partitions in position, locks on said end walls for holding said last-named bar in locking position, and means for loosening said side walls from the adherent molded slabs. 15 8. A mold for casting slabs of flat Z-shaped cross section, comprising a bottom plate, two end walls and two side walls hinged to said bottom plate so as to be able to be swung down into the plane of the latter, said side walls carrying inside each a 20 series of projections arranged in a comb-like manner, the projections of one side wall being staggered relatively to those of the other side wall, a partition arranged in each gap 25 existing between two adjacent projections, said partitions extending from the base of the gaps up to the crests of the projections of the other side wall, bars pivoted to one of the end walls and adapted to be put on 30 the side walls taking their operative position, locking means for said bars in their operative position, a bar extending from one end wall to the other in order to lock said partitions in position, locks on said end walls for holding said last-named bar in locking position, an oppositely threaded nut mounted for rotation on each end wall, a left-hand threaded and a right-hand threaded screw bolt engaged by said nut and adapted to move said side walls outwardly upon said nut being rotated. 35 9. A mold for casting slabs of flat Z-shaped cross section, comprising a bottom plate, two end walls and two side walls hinged to said bottom plate so as to be able to be swung down into the plane of the latter, said side walls carrying inside each a series of projections arranged in a comb-like manner, the projections of one side wall being staggered relatively to those of the other side wall, a partition arranged in each gap 40 existing between two adjacent projections, said partitions extending from the base of the gaps up to the crests of the projections of the other side wall, easily detachable means for locking said side walls and said partitions in operative position, means for locking said locking means in locking position and means for loosening said side walls from the adherent molded slabs. 45 50 55 60

The foregoing specification signed at Cologne, Germany, this 29th day of September, 1925.

CARL BETTERMANN.
